UNITED STATES PATENT OFFICE.

CHESTER E. BAUM AND ROBERT A. PEACOCK, OF DELAWARE CITY, DELAWARE.

COMBINED ROCKING AND REVOLVING CHAIR.

1,395,698.

Specification of Letters Patent.

Patented Nov. 1, 1921.

Application filed May 17, 1920. Serial No. 382,100.

To all whom it may concern:

Be it known that we, CHESTER E. BAUM and ROBERT A. PEACOCK, citizens of the United States, residing at Delaware City, in the county of New Castle and State of Delaware, have invented certain new and useful Improvements in Combined Rocking and Revolving Chairs, of which the following is a specification.

10 This invention relates to combined rocking and revolving chairs, and more particularly to such chairs in which there is a universal rocking motion.

15 The particular adaptation which has been selected for illustration is a chair or device specifically adapted for use by small children, whereby they may be placed in a safe place and amused while at the same time affording them opportunity for necessary

20 exercising without attendant dangers.

The invention consists broadly in the provision of a rocking base with a surmounted chair or seat, which is capable of a revolving motion in relation to the rocking platform.

25 More specifically it consists of a rocking platform surmounting a segment of a sphere whereby universal rocking movement of the platform may be obtained, and a chair or seat mounted upon an auxiliary platform, which is capable of horizontally revolving motion with respect to the rocking platform.

30 The object of the invention is the production of an amusement chair and exerciser, particularly for children of tender age. Another object of the invention is the provision in such a chair of adequate safeguards against injury to the user. Other and further objects of the invention will hereinafter appear in the following description, and the 40 novel features thereof will be particularly pointed out in the appended claims.

In the drawings,

Figure 1 is a plan view of the chair,

Fig. 2 is an elevation thereof, with certain 45 of the parts shown in section, and

Figs. 3 and 4 are views of the coupling member, by which the rocking and revolving platforms are connected.

The numeral 1 is used to designate the 50 rocking platform, which is made of wood, surmounting a bowl 2 in the form of a segment of a sphere, which bowl is of sheet material. The bowl is provided with a flange 3, which is attached to the under side 55 of the rocking platform by screws 4. A

filler member 5 of wood or other suitable material may be used to brace or stiffen the sheet metal bowl, although the bowl may be made of sufficiently stout material to require no such bracing, or the metal bowl may be 60 omitted and the wooden filler used as a rocking surface for the chair, in which event it will be suitably fastened to the rocking platform. The curvature of the bowl is selected with a view to securing a very gentle rock or roll to the chair. The rocking platform is centrally mounted upon the bowl and is of an increased diameter to provide a projecting portion around the bowl, so that in the 65 rocking motion of the chair the periphery of the platform will act as a stop or limit, insuring safety in the use of the device.

Revolutionarily mounted upon the rocking platform is an auxiliary platform 6 upon which is provided a seat 7 comprising a bottom 8, 75 uprights 9 and a body support 10. The auxiliary or revolving platform is extended forward from the open portion of the seat proper sufficiently to receive the legs of the occupant, but otherwise conforms generally 80 to the contour of the seat proper. This seat is attached to the revolving platform by screws or any other suitable means.

The rocking and revolving platforms are connected together by a coupling 11, which 85 is placed centrally of the rocking platform. The revolving platform, however, is mounted eccentrically of the rocking platform in order to secure equilibrium when the chair is occupied that the rocking motion of the 90 device may be produced with slight effort upon the part of the occupant.

The coupling may be of any approved form for permitting a rotary movement between the parts, but the one chosen for illustration comprises a male member 12 and a female member 13. The male member is provided with a base 14 which is inset in the bottom of the revolving platform, said base having projecting therefrom a stud 15 100 provided with an annular groove 17. The female member is mounted centrally upon the rocking platform and is provided with an upstanding portion 18 having a bore 19 into which the stud of the male member 105 takes. A screw 20 is screwed into a threaded aperture in the upstanding portion 18 and the reduced end thereof fits within the groove 17 of the male member when the parts are assembled, there being clearance 110

sufficient between the screw end and the groove to permit easy revolving motion.

Mounted upon the rocking platform is a hand rail 21 supported by brace members 5 22, which are so curved as to permit of ample space for the movement of the revolving platform and yet bring the hand rail 21 into easy access of the occupant of the device. The brace members are screw 10 threaded at one end to screw into the hand rail as shown at 23 and are provided at the upper end with feet 24 by which they are attached by screws to the rocking platform.

In the use of the chair the occupant is 15 placed in the seat proper and strapped therein if desirable with the legs projecting beyond the seat and supported upon the front portion of the revolving platform. The offset mounting of the revolving plat- 20 form upon the rocking platform insures when the device is occupied an upright position thereof. A slight movement of the body of the occupant will cause the device to rock upon the bowl member and another 25 slight movement of the body of the occupant will cause the completing of the rock- ing cycle. If the occupant desires to face in any other direction, the hand rail, which is conveniently located, is grasped and the 30 revolving platform caused to turn upon the rocking platform by a slight pull in the desired direction. The curvature of the bowl is such that the rocking motion pro- duced is even and gentle.

35 It is obvious that a device has been de- vised, particularly for young children, which will afford a means of exercising as well as amusement, and that the easy curva- ture of the bowl together with the project- 40 ing periphery of the rocking platform and the provision of the hand rail and extended foot board contribute to making the device a safe one for the use of children of tender years.

45 Having described the invention, what is claimed as new is:

1. An exercising chair comprising a uni- 50 versal rocking base, a chair or seat mounted upon said base and having independent rotary movement thereon, and a hand rail

supported by the base and surrounding said chair or seat.

2. In a combined rocking and revolving chair, the combination of a universally 55 rocking base comprising a spherical rock- ing surface and a platform extended beyond the rocking surface to limit the rocking movement, a revolving seat support mounted upon the said platform, a seat or chair supported thereon, said support being ex- 60 tended beyond the seat member to provide a support for the legs of the occupant, and a hand rail supported by the platform and accessible to the occupant of the seat.

3. In a combined rocking and revolving 65 chair, the combination of a rocking base comprising a section of a sphere, and a re- volving chair mounted directed above said rocking base and eccentrically thereof.

4. In an amusement or exercising device, 70 the combination of a universally rocking base, a seat, means for mounting said seat upon said base to freely revolve thereon, and means supported on said base and with re- 75 lation to which the seat is revoluble for per- mitting engagement by the occupant of the seat to pivotally turn the seat upon the base.

5. In a combined rocking and revolving chair, the combination of a universally rock- 80 ing base, a revolving occupant support com- prising body and leg sections and so mount- ed upon said base that when occupied the leg portion will substantially counterbal- ance the body portion.

6. In a combined rocking and revolving 85 chair, the combination of a universally rock- ing base comprising a spherical rocking sur- face and a platform extended beyond the rock- 90 ing surface to limit the rocking move- ment, and a revolving occupant support com- prising a seat portion and an extended leg portion and so mounted upon said plat- form that when occupied the leg portion will 95 substantially counterbalance the body portion.

In testimony whereof we affix our signatures.

CHESTER E. BAUM,
ROBERT A. PEACOCK.
